UNITED STATES PATENT OFFICE.

THOMAS W. TUSTIN, OF HOFFMAN, PENNSYLVANIA.

STOP-MOTION FOR KNITTING-MACHINES.

SPECIFICATION forming part of Letters Patent No. 790,604, dated May 23, 1905.

Application filed March 30, 1904. Serial No. 200,671.

To all whom it may concern:

- Be it known that I, THOMAS W. TUSTIN, a citizen of the United States, residing at Hoffman, Lehigh county, State of Pennsylvania, have invented certain new and useful Improvements in Stop-Motions for Knitting-Machines, of which the following is a specification, reference being had therein to the accompanying drawings.
- 10 My invention relates to stop-motions for knitting-machines, and more particularly to that class in which the bobbins are fixed in relation to the rotating parts of the machine, although not entirely confined to that particular construction, as the same can be used on machines wherein the bobbins are made to rotate around the needles.

The object of my invention is to provide a device of the class described whereby the machine is stopped whenever the yarn or thread becomes caught on the bobbin, where it becomes taut from any cause, or is snarled or tangled in any way. It also provides a mechanism for stopping the machine whenever there is a knot, bur, or other defect in the yarn or thread which it would be undesirable to permit to pass to the needles and be knit in the garment or where any other obstructions pass from the bobbin toward the needles or where the supply of thread or yarn becomes suddenly exhausted or loose ends occur in the winding of the yarn on the bobbin, my device being so constructed and operated that the stopping of the machine takes place before the obstruction or loose end can reach the needles and, in cases of obstruction, before the breaking of the yarn ensues.

A further object of my invention is to provide a stop-motion for knitting-machines that shall be operated automatically and one in which simplicity and inexpensiveness of construction are combined with durability and effectiveness in operation.

In the accompanying drawings, forming a part of the specification, I have illustrated a preferred embodiment of my invention, and although it will be obvious that certain modifications of form and arrangement of parts will suggest themselves to the skilled operator and mechanic such modifications come well

within the spirit of my invention as disclosed and claimed, and I do not, therefore, desire to be limited to the exact construction and arrangement shown.

In the drawings, Figure 1 is a perspective view of my improved stop mechanism. Fig. 2 is an enlarged top plan of the rear portion. Fig. 3 is a rear elevation of Fig. 2. Fig. 4 is a perspective view of the sustaining mechanism for the weights. Fig. 5 is a diagrammatic horizontal section showing the belt-shifting mechanism.

Like letters of reference designate similar parts in all the figures of the drawings.

A designates a standard or post which is suitably mounted on a base of frame B. Slidably mounted on this standard is a small bracket C. This bracket is provided with an upwardly-projecting lug on which is pivotally mounted a bifurcated lever D, having two arms *a* rigidly secured to the rear end of the lever, one on each fork and extending rearwardly, one of the arms passing on each side of the standard A, as shown. Swinging loosely in holes in each side of the bracket C are two yarn-guiding arms *b*. These arms are comprised of rods having one end bent at right angles with the rod, and this end fits in the hole in the side of the bracket. Each of these arms *b* is provided with a hole near the outer end thereof, as shown at *c*, through which the yarn or thread passes on its way to the needles. Mounted on the top of the standard or post A is another bracket, E, and secured thereto and extending rearwardly therefrom is a rod *d*, on which are mounted two pulley-wheels F.

G designates two rock-shafts turning in suitable bearings in the bracket E, and near the forward end of each shaft a plurality of fingers *e* are rigidly mounted thereon. These fingers are preferably three in number and are arranged side by side in the same manner as the tines on a fork, and underneath these fingers and rigidly secured to the bracket E are two outwardly-projecting fingers or arms L, each having a shorter prong *j* projecting downward therefrom and disposed at an oblique angle therewith and forming a slide for the yarn when it slips off the fingers *e*, the ob-

ject of these prongs being to deflect the yarn or thread from the fingers. On the rear of each of said shafts G a lever H is movably mounted. These levers are arranged on the 5 shafts so as to extend directly over the pulley-wheels F, one lever projecting over each wheel, as shown, and to the ends of these levers are secured chains f, one chain being secured to each lever. Suspended by these 10 chains over the arms a are two U-shaped weights I, one of the weights being attached to the end of each chain. Adjustably secured by a set-screw to each of the shafts G, near the rear end thereof, is a small lug or stud g, 15 and between this lug and the lever H a spiral spring is arranged, one end of said spring being secured to the lever H and the other end being secured to the lug or stud g, the object of the lug being to regulate the tension on 20 the spring, the spring being so arranged that when the fingers e are pulled down, thus turning the shaft G, around which the spiral spring is coiled, and also turning the lug, the spring becomes tighter and exerts more force 25 in elevating the lever H, to which one end of said spring is secured. Another lug, J, is adjustably secured by a set-screw to the shaft G between the lug g and the end of the bracket. This lug is provided with an arm or pin j, 30 which projects therefrom rearwardly and engages with the lever H, the object of the pin j being to limit the movement of the arm H under spring tension when the tension on the shaft G is removed. The lever H, which is 35 movably mounted on the shaft G, is actuated by the spring h. This spring being secured to the lug g also actuates the shaft G, and the lug J, carrying the arm or pin j, being secured by set-screw on said shaft is also actuated by the spring by means of said shaft. 40 When the yarn slips from the fingers e from any cause, said fingers are released, permitting the shaft to rotate in activity according to the strength of the spring. The weight I is pulling, according to its gravity, on the lever H, the tension of said spring h being 45 against the weight. Secured to the rear of the bracket E and projecting rearwardly over the pulley-wheels F, and consequently over 50 the levers H, is an elevated rod or arm K, with which the said levers H come in contact when raised and are held in place, the object of said elevated arm being to permit the levers H to rise but a short distance above the 55 pulley-wheels F, thus shortening the distance of the dropping of the weights when any obstruction appears in the yarn causing it to be pulled off the fingers e.

M designates a bracket or member which is 60 secured to the bed-plate of a knitting-machine in any suitable manner. Pivotedly mounted on this bracket is a small lever k, the bracket and lever being arranged to turn on the pivotal screw m. This lever k and the bifurcated 65 lever D are connected by means of the rod N,

which is pivotally mounted or fulcrumed on both of said levers.

In operation the yarn or thread O is passed from the bobbins R through the holes c in the arms b, thence alternately over the fingers e and under the fingers L in front of the short prongs k, as shown, and thence to the needles. When the needles are working, the 70 yarn or thread is drawn taut, and this action depresses the fingers e, which intermesh with the lower fingers L, the said fingers L passing through the spaces between the upper fingers e. The fingers e being rigidly secured to the rock-shaft G cause the same to turn in the 75 bearings when the said fingers are lowered. The turning of the shaft causes the lug g, 80 which is adjustably secured thereto by a set-screw, to turn, and one end of the spring h being secured to the lug the tension upon the spring is thus augmented. The other end of 85 the spring is secured to the lever H, and when the spring tightens by reason of the turning of the lug g it raises the lever so that the end thereof strikes the upwardly and rearwardly projecting rod K and is there held in 90 place. The chains f being secured to the ends of the levers H are thus raised, and with them the weights I, which otherwise rest on the arms a, and this permits the forward end of the bifurcated lever D to fall slightly. By 95 means of the rod N the rear end of the lever k is depressed, thus raising the forward end thereof. When a knot, tangle, bur, or other defect appears in the yarn or thread, it will 100 not pass through the holes c, which are only large enough to admit of the free passage of the yarn or thread; but stopping causes the 105 yarn to draw taut enough to depress the fingers e until the yarn slips off the ends thereof and is deflected from the fingers by means of the shorter prongs j. This releases the 110 fingers e and the weights I, by means of the shaft G and the lug J pull the levers down so that the weights drop upon the arms a, causing them to be depressed. This action 115 raises the forward end of the lever D, which raises the rod N with it. The rear end of the lever k being secured to the rod N is consequently raised, and this lowers the forward 120 end of said lever, bringing it into contact with a lug m' or other suitable projection on the cam-surface of the machine, which said cam-surface is on the power-shaft. The cam-surface being in motion and revolving on its axis, the 125 contact of the lever k with the lugs or projections thereon causes the bracket M to be thrown around on its pivotal screw m. The arm n on said bracket engages with an upwardly-projecting lug or pin Q on the end of the link p which is connected with the bell-crank lever o. This bell-crank lever is connected with a belt-shifting device q. When 130 the forward end of the lever k is turned by being brought in contact with the lugs on the cam-surface of the machine, as aforesaid, the

arm *n* engaging with the lug or pin *Q* causes the bell-crank lever to be operated by means of the connecting-link *p*, and the belt-shifting device being operated by said bell-crank lever pulls the belt *R* off of the revolving belt-wheel onto the loose pulley *P*, where it continues to revolve without moving the needles. The belt-shifting device is provided with a handle *r* as a means whereby the belt may 10 be thrown back to its normal or operative position.

Having thus described my said invention, what I claim as new, and desire to secure by Letters Patent of the United States, is—

15 1. In a stop-motion mechanism for textile-machines, the combination with means for stopping the machine, of pivotally-mounted fingers operatively connected therewith and adapted to be held, while in operation, by the tension of the yarn, fixed fingers provided with downwardly and outwardly projecting prongs adapted to throw the yarn outward when the pivotally-mounted fingers are depressed by any increased tension of the yarn 20 and discharge it from the fingers, and yielding means for operating said fingers.

2. In a stop-motion mechanism for textile-machines, the combination with means for stopping the machine, of a rock-shaft journaled in a suitable support and provided with 30 an arm and with fingers constituting in effect a bell-crank lever, other fingers fixed in the support and adapted to intermesh with the movable fingers which are held in that position by the tension of the yarn, downwardly and outwardly projecting prongs secured to the fixed fingers and adapted to throw the yarn outward when said movable fingers are depressed by any increased tension of the yarn 35 40 thus removing the yarn from beyond the reach of such fingers, a connection between the arm and the means for stopping the machine whereby the separation of the two sets of fingers will effect the stopping of the machine, and yielding means tending to separate the fingers against the tension of the yarn whereby an interruption in the feeding of the 45 50 yarn will release the fingers and stop the machine.

5. In a stop-motion mechanism for textile-machines, the combination with means for stopping the machine, of a rock-shaft journaled in a suitable support and provided with an arm and with fingers constituting in effect 55 a bell-crank lever, other fingers fixed in the support and adapted to intermesh with the movable fingers which are held in that position by the tension of the yarn, a connection between the arm and the means for stopping 60 the machine, a guide for the yarn so formed as to intercept the passage of any obstruction, means tending to separate the fingers against the tension of the yarn, and means for discharging the yarn between the fingers whenever an interruption occurs in the feeding of 65

the yarn whereby the fingers are allowed to separate resulting in the stopping of the machine.

4. In a stop-motion mechanism for textile-machines, the combination, with means for stopping the machine, of pivotally-mounted fingers operatively connected therewith and adapted to be held under control by the tension of the yarn, fixed fingers provided with means for discharging the yarn from the movable fingers when the tension is increased, and yielding means adapted to operate the pivotally-mounted fingers.

5. In a stop-motion mechanism for textile-machines, the combination with means for stopping the machine, of a rock-shaft journaled in a suitable support, an arm carried by said shaft and connected therewith, a spring connecting said arm with the shaft in a yielding manner, a connection between the means 80 for stopping the machine and the arm, fingers carried by the shaft and movable therewith, other fingers fixed in the support, the two sets of fingers being adapted to receive the yarn and to be held together thereby, yielding means 85 tending to separate the members against the tension of the yarn whereby an interruption of the feeding of the yarn will release the fingers permitting the rock-shaft to stop the machine.

6. In a stop-motion mechanism for textile-machines, the combination with means for stopping the machine, of a rock-shaft journaled in a suitable support, an arm loosely mounted on said shaft, a spring effecting a 90 yielding connection between the arm and the shaft, a lug carried by the shaft and limiting the movement of the arm, fingers carried by, and movable with, the shaft, other fingers fixed to the support, the two sets of fingers 95 100 adapted to intermesh and to be held in that position by the yarn, yielding means tending to separate the fingers, and a connection between the arm and the means for stopping the machine whereby an interruption in the feeding of the yarn will rock the shaft and stop the machine.

7. In a stop-motion mechanism for textile-machines, the combination with means for stopping the machine, of a rock-shaft journaled in a suitable support, an arm loosely mounted on said shaft, a spring effecting a yielding connection between the arm and the shaft, means for regulating the tension of the spring, a lug adjustably mounted on the shaft 110 and arranged to limit the movement of the arm, fingers carried by and movable with the shaft, other fingers fixed in the support, the two sets of fingers adapted to intermesh and to be held in that position by the yarn, yielding means tending to separate the fingers, and a connection between the arm and the means for stopping the machine whereby an interruption in the feeding of the yarn will rock the shaft and stop the machine.

8. In a stop-motion mechanism for textile-machines, the combination with means for stopping the machine, of a rock-shaft journaled in a suitable support, an arm loosely mounted on said shaft, a spring effecting a yielding connection between the arm and the shaft, means for regulating the tension of the spring, a lug adjustably mounted on the shaft and arranged to limit the movement of the 10 arm, fingers carried by and movable with the shaft, other fingers fixed in the support, the two sets of fingers adapted to intermesh and to be held in that position by the yarn, yielding means tending to separate the fingers, a 15 guide for the yarn so arranged as to intercept any obstruction therein and to withdraw the yarn from the fingers permitting them to separate, and a connection between the arm and the means for stopping the machine whereby 20 an interruption in the feeding of the yarn will rock the shaft and stop the machine.

9. In a stop-motion mechanism for textile-machines, the combination with means for stopping the machine comprising a lever, of a 25 rock-shaft journaled in a suitable support, an arm loosely mounted on said shaft, a spring effecting a yielding connection between the arm and the shaft, means for regulating the tension of the spring, a lug adjustably mounted 30 on the shaft and arranged to limit the movement of the arm, fingers carried by and movable with the shaft, other fingers fixed in the support, the two sets of fingers adapted to intermesh and to be held in that position 35 by the yarn, yielding means tending to separate the fingers, a guide for the yarn so arranged as to intercept any obstruction therein and to withdraw the yarn from the fingers permitting them to separate, and a connection 40 between the arm and the means for stopping the machine whereby an interruption in the feeding of the yarn will rock the shaft and stop the machine.

10. In a stop-motion mechanism for textile-machines, the combination with means for stopping the machine, of a lever, a connection 45 between one arm of the lever and the stopping means, a rock-shaft journaled in a suitable support, an arm loosely mounted on said shaft, a spring effecting a yielding connection between 50 the arm and the shaft, a lug carried by the shaft and limiting the movement of the arm, fingers carried by and movable with the shaft, other fingers fixed to the support, the two sets of fingers adapted to intermesh and to be held in that position by the yarn, yielding 55 means tending to separate the fingers, and a connection between the arm and the means for stopping the machine whereby an interruption 60 in the feeding of the yarn will rock the shaft and stop the machine.

11. In a stop-motion mechanism for textile-machines, the combination with means for stopping the machine, of a lever, a connection 65 between one arm of the lever and the stopping

means, a rock-shaft journaled in a suitable support, fingers carried by the shaft and adapted to receive the yarn, an arm carried by the shaft, a weight suspended from the arm and tending to rock the shaft, and to bear upon 70 said lever whereby an interruption in the feeding of the yarn will release the weight and operate the lever to stop the machine.

12. In a stop-motion mechanism for textile-machines, the combination with means for 75 stopping the machine, of a lever pivoted in a suitable support with one of its arms in operative relation to such stopping means, a second lever pivoted in the other arm of the first lever with one of its arms so arranged as to 80 be capable of being brought in the path of a moving portion of the machine, a rock-shaft journaled in a suitable support, an arm carried by the shaft, a connection between the arm and the last-named lever, fingers carried 85 by the shaft and adapted to receive the yarn, yielding means tending to rock the shaft against the tension of the yarn whereby when the tension of the yarn is removed the shaft will rock and operate the levers to effect the 90 stopping of the machine.

13. In a stop-motion mechanism for textile-machines, the combination with means for stopping the machine, of a lever pivoted in a suitable support with one of its arms in operative 95 relation to such stopping means, a second lever pivoted in the other arm of the first-named lever with one of its arms so arranged as to be capable of being brought into the path of a moving portion of the machine, a 100 rock-shaft journaled in a suitable support, an arm carried by said shaft, fingers carried by the shaft and movable therewith, other fingers fixed in the support, the two sets of fingers adapted to intermesh and to be held together 105 by the tension of the yarn, an arm carried by the shaft, a weight suspended from the arm and tending to rock the shaft and separate the fingers against the tension of the yarn and then to bear upon the last-named lever whereby an interruption in the feeding of the yarn 110 will permit the operation of the levers and stop the machine.

14. In a stop-motion mechanism for textile-machines, the combination with means for 115 stopping the machine, of a lever pivoted in a suitable support with one of its arms in operative relation to said stopping means, a second lever pivoted in the other arm of the first-named lever with one of its arms so arranged 120 as to be capable of being brought into the path of a moving portion of the machine, a third lever pivoted in a suitable support, a connection between the two last-named levers, a rock-shaft journaled in the support, 125 fingers carried by the shaft and movable therewith, other fingers fixed in the support, the two sets of fingers adapted to intermesh and to be held in that position by the tension of the yarn, prongs carried by the fixed fingers 130

in such relation as to deflect the yarn from the fingers upon an increase in the tension, a guide so arranged as to intercept any obstruction in the yarn, an arm carried by the shaft, a spring 5 effecting a yielding connection between the arm and the shaft, a lug limiting the movement of the arm relative to the shaft, a weight suspended from the arm and tending to rock the shaft and separate the two fingers against 10 the tension of the yarn, the relation of the weight to the last-named lever being such that as the shaft is rocked the weights will bear

upon the lever whereby an obstruction in the yarn will serve to increase the tension, and release the movable fingers permitting the 15 shaft to rock and the stopping mechanism to be brought into operation by means of the levers.

In testimony whereof I hereunto affix my signature in presence of two witnesses.

THOMAS W. TUSTIN.
